(57) **CLAIM**

The ornamental design for a compact grasping device, as shown and described.

DESCRIPTION

FIG. 1 is a front perspective view of an embodiment of a compact grasping device in accordance with the present new design, wherein the grasping portion is shown in an extended position;

FIG. 2 is a top plan view of the embodiment of the compact grasping device of FIG. 1;

FIG. 3 is a bottom plan view of the embodiment of the compact grasping device of FIG. 1, wherein the grasping portion is shown in the extended position;

FIG. 4 is a left side plan view and right side plan view of the embodiment of the compact grasping device of FIG. 1, wherein the grasping portion is shown in the extended position;

FIG. 5 is a front plan view of the embodiment of the compact grasping device of FIG. 1, wherein the grasping portion is shown in the extended position; and,

FIG. 6 is a back plan view of the embodiment of the compact grasping device of FIG. 1, wherein the grasping portion is shown in the extended position.

The broken lines shown represent unclaimed subject matter and form no part of the claimed design.

1 Claim, 4 Drawing Sheets
